UNITED STATES PATENT OFFICE.

FREDERICK JOHN ESMOND, OF VANCOUVER, CANADA, ASSIGNOR OF ONE-THIRD TO FRED T. COPE AND CHARLES FREY, OF VANCOUVER, CANADA.

ELECTRICAL CONTACT-CLAMP.

SPECIFICATION forming part of Letters Patent No. 740,358, dated September 29, 1903.

Application filed July 10, 1902. Serial No. 114,984. (No model.)

To all whom it may concern:

Be it known that I, FREDERICK JOHN ESMOND, a citizen of the Dominion of Canada, residing at Vancouver, in the Province of 5 British Columbia, Canada, have invented a new and useful Electrical Contact-Clamp, of which the following is a specification.

My invention relates to an improved electrical contact-clamp designed for wherever 10 screw connections are at present used, but especially applicable to supersede such in "cut-outs," branch "boxes," or "rosettes" where it enables an efficient contact with the line-wires to be simply and expeditiously 15 made.

The device is fully described and illustrated in the following specification and drawings, in which—

Figure 1 is a side elevation of the clamp to 20 an enlarged scale; Fig. 2, a plan of the same; Fig. 3, an end elevation in the direction of the arrow; Fig. 4, a side elevation of a modified form; Fig. 5, a section of a ceiling-rosette, showing the application of the clamp in 25 such; and Fig. 6, a cross-section on the line *a a* in Fig. 1.

In the drawings, *P* indicates the insulating-base to which the clamp is secured, and *W* the wire to be connected.

30 In the preferred form my device consists of a base-plate 2, formed from a strip of sheet metal and having a depressed groove 2^a, extending longitudinally along the center of its width for about two-thirds of its length.

35 The strip is doubled back on itself, as at 3, and this portion forms the means by which the clamp as a whole is secured to the insulating-base by the screw 4, and to which the terminal screw 5 is connected in the usual 40 manner. The strip is then bent upward for a short distance and then resumes the horizontal, as at 6, terminating in the hinge to which the clamping member 7 is connected by the hinge-pin 8. The clamping member 45 7 is constructed in one piece, the portion 7^b, which forms the hinge attachment, being die struck from the center of the body and bent over. One part of the clamp member projects outward toward the end and is bent 50 down toward the base-plate 2, being provided toward the end with a groove 7^a to oppose the

groove 2^a of the base-plate. As this portion of the clamp member forms a lever by which the clamp is operated the extreme end is bent slightly upward to form an engagement for 55 the finger-nail. On the opposite side of the hinge-pin the clamp member is bent down toward the base-plate in a cam or eccentric form, as 7^c, and is provided with an opposing groove, as before, to engage the wire which 60 it is designed to clamp.

In application the clamp member is turned into the position indicated by dotted lines in Fig. 1, and the cleaned end of the wire it is desired to connect being placed in the groove 65 2^a the clamp is brought down to the position as drawn, the end of 7^c rubbing a good metallic contact in passing the center and the resilience of the portion 5, to which the clamp is hinged, enabling the contact-bearings to 70 adapt themselves to variation in the thickness of the wire.

The opposing grooves of the base and clamp permit a very efficient contact to be made, as the wire is partially encircled by the clamping members, and the device may be made conveniently small and of light material, as the current will flow through both top and bottom members of the clamp, to facilitate 75 which it will be noticed that the clamp member 7 beyond the width of the hinge portion is shaped to conform to the outside of the hinge portion of the part 5, which insures an ample contact at the hinge connection.

I do not confine myself to the particular 85 manner of construction here illustrated, as such may be modified to suit the requirements of manufacture and varied conditions of application, and it may for some applications be found sufficient to simply clamp the 90 wire against the insulating-base without providing a conductive base-plate 2. The clamp will, under such conditions, be cheaper to manufacture; but I consider the addition of the base-plate an advantage, as the clamp is 95 then self-contained and independent of the attachment to the insulator, while it has also a greater contact and conductive area.

Fig. 5 shows the application of my clamp to an ordinary ceiling-rosette, *P* being the insulating-base, *p'* the bridge-piece of such, which separates the two connections, and *C*

the cover, secured by the screws 5 and within which are the fuses and their attachments.

Having now particularly described my invention, I declare that what I claim as new, 5 and desire to be protected in by Letters Patent of the United States, is—

A contact-terminal of the class described comprising an insulating base member having groove in its upper face, and an aperture; 10 a base-plate 2 fixedly secured to the insulating-base; a bolt 4 adapted to pass through the aperture in the base member for securing the base-plate 2 to the base member, said base-plate 2 having a portion bent backward 15 upon itself as at 3, and a vertical and a horizontal portion 6, said horizontal portion 6 being disposed in a plane above the base-plate 2; a lever pivotally secured to the horizontal portion 6, said lever including a heel portion 20 7^e forming a cam member and a lever portion

7^a, said lever portion 7^a and said heel portion 7^e each having a concave groove, said base-plate having a similar groove to coact with the concave groove, in the portion 7^e and 7^a, said lever 7 and said base-plate 2 being normally held in engagement with each other and adapted to receive a contact-terminal in the groove portions thereof, a binding-screw 5 mounted in the portion 3 for securing a second contact-terminal, substantially as shown 30 and described.

In testimony whereof I have hereunto signed my name to this specification, in the presence of two subscribing witnesses, at Vancouver, British Columbia, this 26th day of 35 April, 1902.

FREDERICK JOHN ESMOND.
